UNITED STATES PATENT OFFICE.

HARRY L. DUNNETT, OF KANSAS CITY, MISSOURI, ASSIGNOR TO REGAL MANUFACTURING COMPANY, OF KANSAS CITY, MISSOURI, A CORPORATION OF MISSOURI.

POWDER-DISPENSING BOX.

1,371,356.

Specification of Letters Patent. Patented Mar. 15, 1921.

Application filed October 1, 1920. Serial No. 414,000.

To all whom it may concern:

Be it known that I, HARRY L. DUNNETT, a citizen of the United States, residing at Kansas City, in the county of Jackson and 5 State of Missouri, have invented certain new and useful Improvements in Powder-Dispensing Boxes; and I do declare the following to be a full, clear, and exact description of the invention, such as will enable others skilled in the art to which it 10 appertains to make and use the same, reference being had to the accompanying drawings, and to the letters and figures of reference marked thereon, which form a part of 15 this specification.

This invention relates to powder dispensing boxes, the main object being to provide a box adapted to contain insect powder, the box being in the form of a bellows with a 20 discharge opening through which the powder may be blown when it is desired to apply it.

The invention further contemplates a novel construction of dispensing carton or 25 box which may be conveniently constructed, which will be efficient in practice and which will be inexpensive to make.

The novel features of my invention will be better understood by reference to the accompanying drawings, in which—

Figure 1 is a perspective view of a dispensing container constructed in accordance with my invention, parts being broken away to show the interior construction 35 thereof.

Fig. 2 is a vertical, longitudinal, sectional view through the same, and

Fig. 3 is an end view of the bellows spring and its end anchors.

The container proper may consist of an 40 ordinary carton or box 1, formed from a single blank in any well known manner. One end, for example 2, is provided with a discharge opening 3, originally covered by 45 a wrapper 1' for the box 1 is generally covered by a label. The wrapper is sufficient to prevent the accidental spilling of the contents of the box during transportation

and upon the shelf of the merchant. In order to render the discharge opening 3 50 effective, it will be only necessary to punch the wrapper at the point 3 to complete the opening whereupon the contents may be discharged.

I have provided an efficient means for 55 rendering the flexible top and bottom portions 4 and 5 effective as bellows to cause an ejection of the insecticide or other powder within the receptacle. The novel means for converting the box into a bellows is best 60 shown in Fig. 3 as consisting of an upper anchor member 6 and a lower anchor member 7, the respective anchor members being preferably co-extensive with the top and bottom of the box and they preferably lie 65 in close proximity thereto with an expansion spring 8 interposed between them. The ends of the expansion spring 8 are adapted to engage strips or securing members 9 and 10 cut from the body portions of the anchor 70 members 6 and 7 by longitudinally slitting them so that the strips may be pulled away from the main body portion of their respective members 6 or 7 and allow engaging spaces for the ends 11 and 12 of the spring 75 8, the ends of the coil being adapted to engage between the strips 9 and 10 and the portions 6 and 7 as shown. The bellows attachment is then placed within the blank, which is then folded and pasted so that the 80 parts will have the position shown in Figs. 1 and 2.

If the opening 3 is uncovered and the operator grasps the top and bottom of the box between the thumb and fingers and 85 presses after a manner common to a bellows operation, the exhausted air will force the powder in the container through the opening 3. When the pressure is relieved, additional air will pass into the box through the 90 opening 3, ready to be expanded by the next compression to carry with it the powder, as will be well understood.

From the foregoing it will be seen that the device is easily constructed, simple in 95 operation, inexpensive to make and that it

will efficiently perform the function for which it is intended.

What I claim and desire to secure by Letters-Patent is:

- 5 1. A dispensing box for powders comprising an inclosing casing having flexible walls and a discharge opening, a coil spring within the casing, and anchors for the ends of the spring comprising blocks having out-

standing strips engaging the ends of the 10 coil spring.

2. A dispensing box for powder comprising an inclosing casing, anchor members within the rectangular casing having intermediate strip portions cut therefrom, and 15 a coil spring connected to the strips.

In testimony whereof I affix my signature.

HARRY L. DUNNETT.
